UNITED STATES PATENT OFFICE.

EDWARD L. PENDLETON, OF LEXINGTON, KENTUCKY.

METHOD AND APPARATUS FOR DECORTICATING AND SCUTCHING.

Application filed March 3, 1925. Serial No. 12,980.

This invention relates to an improved machine for treating fibrous materials or plants for the removal of the woody central portion from the fibrous outer bark.

5 The primary object of this invention is the provision of a decorticating or scutching machine embodying a novel arrangement of decorticating mechanisms adapted to act in a novel manner upon plants such as hemp, 10 flax, jute, ramie, sisal, or the like, for the proper separation of the fibrous outer bark from the woody central portion.

A further object of this invention is the provision of a shiving or decorticating machine adapted to economically and expeditiously reclaim the valuable fiber portions of plants, without the attendant waste which is a characteristic of so many fiber treating machines.

20 A further object of this invention is the provision of a novel method of treating fibrous plants, to obtain the greatest yield of fiber material, and to deliver the fibrous material in proper position for binding and 25 handling.

Other objects and advantages of this invention will be apparent during the course of the following detailed description.

In the drawings, wherein for the purpose 30 of illustration is shown only a preferred embodiment of the improved decorticating machine.

Figure 1 is a side elevation of the improved decorticating apparatus.

35 Figure 2 is an end elevation of the improved machine, showing the entrance end of the machine, with certain parts broken away to more clearly illustrate other parts.

Figure 3 is a fragmentary plan view of 40 the improved machine, showing more particularly the details of the machine at the entrance end.

Figures 4 and 5 are cross sectional views 45 taken substantially on their respective lines in Figure 1 of the drawings.

Figures 6, 7, and 8 are cross sectional views taken transversely of the improved machine similar to Figure 5, showing more particularly different positions of a recorti- 50 cating mechanism employed in the improved machine.

Figure 9 is a fragmentary view, partly in section, showing an improved mechanism 55 adapted to be used for the purpose of shak- ing fibers after the breaking of the same

to loosen the same from the woody central portions of the plants treated, and

Figure 10 is a side elevation of a movable type of breaking jaw employed in one of the decorticating mechanisms.

In the drawings, wherein similar reference characters designate corresponding parts throughout the several views, the letter A may generally designate the improved decorticating machine, which may include a frame B; a first decorticating mechanism C at the entrance end of the machine A; and a second decorticating mechanism D for treatment of plants after passing through the decorticating mechanism C. The first decorticating mechanism C preferably includes a conveyor structure E; breaker structure F; shaker mechanism G; and drive and operating means H. The second mentioned decorticating mechanism D includes a conveyor 75 structure K; breaker mechanism L; shaker means M; and drive or operating means N connected with the drive means H of the first mentioned decorticating mechanism C.

The frame B may be of any approved construction, either wood or metal, and in the preferred instance the same is rectangular, including the longitudinally extending supporting beams 10 and 11, connected at their forward and rear ends by means of cross 85 beams 12. At the rear corners of the frame, vertical posts or standards 15 and 16 are provided, and between the ends of the longitudinal floor beams 10 and 11, vertical posts or standards 17 and 18 are provided. These posts 90 or standards support transverse beams 19, and upon the transverse beams 19 the top longitudinal beams 20 and 21 are supported in spaced parallel relation; the spacing being less than the spacing of the floor beams 10 and 11. The rear ends of the top beams 20 and 21 project rearwardly of the plane in which the intermediate posts 17 and 18 lie, and are not supported at the extreme rear end of the frame B.

100 In connection with the decorticating mechanism C, an auxiliary frame-work is provided, supported by the longitudinal floor beams 10 and 11, and consisting of the rearmost corner posts 13 and 14, and vertical posts 22; the posts 13 and 14 and 22 being of a height to terminate below the plane in which top beams 20 and 21 lie, for the purpose of supporting a platform structure 25, as a part 105 of the decorticating mechanism C. This 110

platform structure 25 comprises the side beams 26, which are supported by the posts 13, 14 and 22, and the extreme ends of said beams 26 project forwardly of the posts 22 for rotatably supporting a horizontal shaft 27 therein, as a connection for the conveying means E and K to be subsequently mentioned. At the extreme rear end the beams 26 project rearwardly of the rear posts 13 and 14, cantilever fashion, and support the boards 29 of the platform thereon.

The conveyor means E preferably comprises a pair of conveyors 30 and 31, rotatably supported in spaced relation at opposite sides of the rear part of the machine, providing a space 32 between the same, within which the breaker mechanism F operates. These conveyors 30 and 31 at their front ends are respectively supported upon rollers 35 and 36 which are keyed to the shaft 27, and at their rear ends said conveyors are rotatably supported upon idler rollers 37 and 38 carried by shafts 39. The platform 25 extends rearwardly of the rear ends of these conveyors 30 and 31, and includes a portion 41 which extends a slight way into the space 32 between said conveyors, and as is illustrated in Figure 3 of the drawings. The conveyors 30 and 31 are thus horizontally disposed for movement between the beams 26, and the same are preferably provided with lugs or flights thereon which during the movement of the conveyors project slightly upwardly from the plane of the top surface 33 of the platform boards 29, in order to grasp the ends of stalks and plants as the stalks and plants are fed from the platform 25 to the conveyors 30 and 31.

The breaker means E of the first decorticating mechanism C preferably includes an upper section or jaw 45, which is stationary; the same preferably being supported by the rear ends of the beams 20 and 21, as is illustrated in Figures 1 and 2 of the drawings. This stationary breaker section 45 is supported by the means 46, and upon the lower surface thereof the same is provided with spaced blades 47 disposed in an inclined or diagonal relation with respect to the longitudinal axis of the machine, and path of travel of the plants or stalks. The breaker mechanism E furthermore includes a movable jaw or section 49 which is pivoted as at 50 beneath the rear end of the platform 25, and which extends forwardly for connection to the operating mechanism H, as will be subsequently described. Upon the upper surface of the free moving section 49, forwardly of the pivot axis 50, said movable section or jaw 49 preferably supports blades 52 in upwardly extending relation, which are inclined at an acute angle with respect to the longitudinal axis of the machine and the path of travel of the plants thru the machine; these blades 52 being disposed in a

meshing parallel relation between the blades 47 of the stationary section 45. The blades 47 and 52, of course, operate in the space 32 between the conveyors, upon the central portions of the stalks as they are fed by the conveyors along the machine, and as will be subsequently described.

Referring at this time to the drive means H for the first decorticating mechanism C, the same includes a main crank shaft 60, transversely supported at the lower rear corner of the frame B, by means of bearings 61, which are preferably carried by the posts 22. One end of this crank shaft 60 extends laterally of the frame B, and is provided with a pulley wheel 62, or analogous element for drive of the said crank shaft. Between the ends of the crank shaft the same is preferably provided with a throw portion 63, which is connected to a bearing 64 at the free swinging end of the breaker jaw 49 by means of a connecting rod 65, substantially after the manner illustrated in Figure 2 of the drawings.

Referring to the shaker means G for the first decorticating mechanism C; the same preferably includes a shaker frame 70, carried in a plane between the stationary and movable breaker jaws 45 and 49, and which includes a plurality of fingers 71 diagonally disposed, and in parallel relation with the blades of the said breaker jaws. The frame 70 furthermore includes a vertical reciprocating rod 72, which is supported by means of a bearing 73 at the forward side of a cross beam 74 carried by the upper ends of the posts 22. This vertically disposed reciprocating rod portion 72 of the frame 70 at the lower end thereof is provided with a segmental cam engaging portion 75, providing a concave cam surface 76 therein which receives an eccentric 77 keyed to the crank shaft 60 adjacent the throw portion 63 of said crank shaft. This rod 72 is threaded for a portion 79 thereon, above a bearing 80 which is carried by an intermediate cross beam 81, disposed below the cross beam 74, and also carried between the posts 22. A nut and washer mechanism 83 is carried in adjustable manner on the threaded portion 79 of the rod portion 72, and between the same and the bearing 80 a compression spring 84 is provided, whose compression may be adjusted by the nut 83, and the function of which compression spring is to normally urge the frame 70 upwardly so that the lower end of the cam segment 75 engages the eccentric 77. The eccentric 77 is provided with a sharp throw portion 86 thereon, which suddenly releases the frame 70 to send the same upwardly responsive to action of the spring 84, in order to quickly shake and agitate the crushed or broken portions of the stalks which are fed between the jaws at the first decorticating mechanism C.

. In the decorticating mechanism D, the conveyor mechanism K thereof is disposed at the longitudinal axis of the frame B, and includes a pair of stationary side plates 85 and 86, supported at their rear ends on the shaft 27, and at their forward ends being supported by a shaft 88 which is carried by an upward and forwardly inclining supporting rod 89; said rod 89 at its lower end being attached to the lower cross beam 12 of the frame B. Between the plates 85 and 86 the conveyor belt 90 is supported, on rollers which are keyed to the shafts 27 and 88; the said belt 90 being of any approved type, and preferably including upwardly extending lugs or flights, as is illustrated in Figure 1 of the drawings. The plates 85 and 86 guard the lower strand of the belt 90, but permit the lugs or flights 92 to project upwardly above the upper edges of said plates, so that the same can grip the stalks or plants thereof and convey the same longitudinally of the frame or machine. At this point it will be well to mention that as the plants are conveyed through the first decorticating mechanism C, they are crushed or broken between the ends thereof, so that as the same are conveyed from the conveyors 30 and 31 to the central conveyor mechanism K, they will bend between the ends thereof and droop inwardly in vertically inclining manner beneath the conveyor K, where the same may be operated upon by the vertically disposed breaker mechanism 35 L of the second decorticating mechanism D.

The breaker mechanism L of the decorticating device D preferably comprises a pair of movable breaker jaws 95 and 96, carried at opposite sides of the central vertical plane 40 of the conveyor K. These jaws are of analogous construction, each of the same preferably comprising a pair of vertical supporting members 97, providing convex faces 98, which support blades 99 thereof in a slightly inclined or diagonal position with respect to the horizontal, preferably at an acute angle thereto. Each of the jaws 95 and 96 are provided with a more closely spaced blade arrangement at the rear end thereof than at 50 the forward end, as is illustrated in Figure 1 of the drawings, and this construction for each of the said jaws or breakers 95 and 96 comprises a support member 100 analogous to the support members 97, disposed parallel 55 with and between the respective vertical support members 97, and which forms an end support for the shorter blades 101 which are carried between the said intermediate supports 100 and the rearmost support 97, as 60 is illustrated in Figure 1 of the drawings. The blades 99 and 101 thus present a convex arrangement for each of the breaker jaws 95 and 96, and the said jaws in their movement are adapted to have a rocking engagement at the convex faces thereof, so that

the blades of the jaws 95 and 96 mesh to properly crush and break the fiber from the pulp of the plants or stalks, in order to properly reclaim the fibrous portion.

Each of the jaws 95 and 96 is supported 70 by means of a pair of arcuate supporting arms 105, which are connected at their lower ends to pivot shafts 106, at the outside surface of the vertical support members 97. At their upper ends arms or connecting members 105 are pivotally supported on shafts 108, upon brackets 109 which depend from the longitudinal top rails 20 and 21.

Referring now to the means of operating the jaws 95 and 96, said means M consists 80 of a pair of shafts 110 and 111 respectively for the jaws 95 and 96, which are suitably carried by bracket portions or bearings 111^a carried by the posts 15 and 16, 17 and 18 of the frame B. Stub shafts 110 and 111 at 85 their rearmost ends are provided with beveled gears 114, and 115 respectively, which are in meshing relation with beveled gears 117 and 118 respectively keyed to the main drive shaft 60. Each of the shafts 110 and 90 111 is provided with a pair of throw portions 120, to which are connected the bracket portions 121 at the lower outside corners of the jaw supports 97, substantially after the manner illustrated in Figure 5 of the drawings. It is readily apparent that upon rotation of the shafts 110 and 111, the jaws 95 and 96 will be moved into rocking engagement at their bladed faces to crush and break the depending ends of the fibers or 100 plants therebetween.

The second decorticating mechanism D also includes a shaker apparatus M, which preferably consists in the provision of a pair of elongated and substantially U-shaped 105 rods 125 and 126, pivotally supported at their forward upturned ends 127 on the supporting arm 89 at the forward end of the machine A, as is illustrated in Figure 1 of the drawings. At their rear upturned ends 110 128 the said rods are pivotally supported in an approved bracket carried by the beam 74, substantially after the manner illustrated in Figure 9 of the drawings. The purpose of providing these two shaker members 125 and 126 is that of shaking the pulp or woody part free from the fiber of the stalks or plants, as can readily be understood by anyone skilled in the art to which this invention relates. The shaker rods 125 and 126 are 115 operated from the reciprocating rod 72, as is illustrated in Figures 4 and 9 of the drawings, by means of providing a forward extension 135 rigid with the rod 72, which at its upper end is pivotally connected to the portions 128 of the long shaker rods 125 and 126 by means of divergent links 136 and 137 respectively, as is illustrated in Figure 4 of the drawings. Thus, as the rod 72 reciprocates 120 incident to the eccentric operation 130

thereof from the shaft 60, the same will cause the shaker rods 125 and 126 to oscillate back and forth and laterally shake the depending ends of the stalks hanging from 5 the central conveyor.

Referring briefly to the cycle of operation and the method of treating the fibrous stalks or plants, the stalks are placed transversely of the machine, on the entrance platform 25. They are fed onto the conveyors 30 and 31 with the intermediate portions thereof extending across the space 32, and as the said conveyors 30 and 31 convey 10 the same forwardly the intermediate portions of the stalks will be crushed and broken between the breaker jaws 45 and 49. The conveyors 30 and 31 are preferably operated at the desired rate of speed by means of a chain connection 140 between the crank 15 shaft 60 and the conveyor shaft 27. The intermediate portions of the stalks are thoroughly crushed, and at the interval between the lifting movement of the jaws 47 and 49, the eccentric 77 of the shaft 60 comes into 20 play to cause release of the eccentric engaging end 76 of the rod 72, so that the spring 84 will snap the frame 70 quickly upwardly against the crushed intermediate portions of the stalks, causing the pulp or woody 25 portion of the plants and stalks to shake free from the fabric portions. At the end of the movement of the stalks upon the conveyor belts of the conveyor means E, the stalks leave the first decorticating mechanism C, and are engaged by the belt 90 of 30 the longitudinal central conveyor K. As the stalks are broken between their ends they drop laterally at each side of the conveyor K, in substantially a vertical position, 35 and are carried forwardly of the machine A by means of the conveyor K, between the jaws 95 and 96 of the breaker means L of the second decorticating mechanism D. The 40 ends of the stalks are thus lowermost, and since they are unbroken, by reason of having been carried along the conveyors 30 and 31, the blades 99 of the jaws 95 and 96 will 45 first engage the same, and rock over them. The stalks will be thoroughly crushed as 50 the vertical ends of the stalks enter the more closely spaced arrangement of the blades 99 and 101. The action of the jaws 95 and 96 may best be seen from the cycle of operation 55 of the jaws, illustrated in Figures 5, 6, 7 and 8. The jaws may be said to permit the entrance of the vertically disposed portions of the stalks which are suspended from the conveyor K, as is illustrated in Figure 6, when the jaws are wide apart. As the crank 60 shafts 110 and 111 continue to rotate, the jaws 95 and 96 will first come together at the top ends thereof, as is illustrated in Figure 7, and the said jaws or breakers will have a rolling contact from this upper arrangement towards the lower ends of said 65

jaws to the position illustrated in Figure 8, thus pressing the stalks from the upper ends to the lower ends by means of crushing them between the meshing blades of the said jaws. The final and released position of the 70 stalks or plants from the jaws or breakers 95 and 96 is illustrated in Figure 4. During the progressive movement of the stalks along the conveyor K, the shaker rods 125 and 126 are of course active in oscillating 75 against the depending portions of the stalks, thoroughly shaking the same free from the pulp or woody portions which has been crushed from the fibers or bark thereof. The shaking of the vertical ends of the fibers on the conveyor K is occasioned at the release of the fibers by the jaws 95 and 96. This action of the shakers also maintains the fibers straight. The reclaimed fibers are delivered at the front end of 80 the machine, properly broken and cleaned, and in the most desirable manner, with the fibers doubled upon themselves, at the central portions thereof, making a "hank" so to speak, which may be easily handled, and 85 not easily tangled.

From the foregoing description of this invention it will be apparent that an improved decorticating machine has been provided, which while the same is relatively simple in 90 character, is highly practical for use in connection with the scutching of fibrous plants or stalks. In many sections of the country farmers refuse to raise certain crops, such as hemp and flax, the fiber of which is desirable, because of the scarcity of labor to harvest and treat the same. A machine possessing 100 the practical characteristics of this machine is therefore an economic necessity both to the farmer and the country at large, in view of the low cost entailed by cleaning of fibrous plants by the same.

Various changes in the shape, size, and arrangement of parts may be made to the form of invention herein shown and described, without departing from the spirit of the same or the scope of the claims.

I claim:

1. That method of treating fibrous plants which consists in breaking the same between the ends thereof, doubling the same upon themselves, and breaking and cleaning the ends thereof.

2. That method of decorticating fibrous plants which consists in breaking and cleaning the said plants at the central portions thereof, doubling each plant upon itself by bending in the center so that the unbroken end portions are adjacently disposed, and then breaking and cleaning the end portions thereof simultaneously.

3. That method of treating fibrous plants which consists in breaking the plants at the central portions thereof, shaking the plants at the central portions thereof to free said 130

- central portions of pulp, breaking the end portions of said plants outwardly of said central portions, and shaking said end portions to free the same of pulp.
- 5 4. That method of treating fibrous plants for reclaiming the fibrous material thereof which consists in breaking the intermediate portions of each of said plants, shaking the intermediate portions of said plants to free 70 the same of pulp and woody central portions, bending said fibrous plants upon themselves to double them at their central portions so that their uncleared and unbroken end portions are disposed in adjacent relation, and 10 15 breaking and cleaning the said adjacently disposed end portions free of pulp and woody central material.
5. In a decorticating machine for treating fibrous plants the combination of a first decorticating mechanism for crushing and shaking the intermediate portions of the plants, and a second decorticating mechanism for receiving the plants after they have been treated by the first decorticating 20 25 mechanism to crush and shake the end portions of said plants.
6. In a machine for treating fibrous plants to free the pulp from the fibrous portions to be reclaimed, a pair of jaws adapted to crush the plants therebetween, a shaker for the plants operating between the jaws, and means for operating the shaker at intervals between the crushing movements of said jaws.
- 30 35 7. In a decorticating machine for treating fibrous plants the combination of a frame, conveyor means, breaker means including jaws, means for moving the jaws with respect to each other, and blades carried by said jaws at their facing sides disposed obliquely with respect to the path of movement of the plants by said conveyor means.
8. In a decorticating machine for treating fibrous plants the combination of a frame, conveyor means, breaker means including 40 45 jaws, means for moving the jaws with respect to each other, blades carried by said jaws at their facing sides disposed obliquely with respect to the path of movement of the plants by said conveyor means, and shaker means operable at intervals between the crushing movements of said jaws including a plurality of blades obliquely disposed with respect to the path of movement of the plants 50 55 by said conveyor means.
9. In a decorticating machine the combination of a frame, a plant conveyor, a crusher arrangement including jaws with blades obliquely disposed with respect to the path of movement of the plants by said conveyor means, and shaker means adapted to act upon the plants at intervals between the crushing movements of the jaws of said breaker means for shaking the pulp free 60 65 from the crushed fibers.
10. In a decorticating machine the combination of a frame, a pair of spaced conveyors adapted to receive the ends of plants thereon for conveying the intermediate portions of said plants over the space between said conveyors and crushing means operable in the space between said conveyors for crushing the intermediate portions of the plants as they are so conveyed. 70
11. In a decorticating machine the combination of a frame, a pair of spaced conveyors adapted to receive the ends of plants thereon for conveying the intermediate portions of said plants over the space between said conveyors, and crushing means operable 75 80 in the space between said conveyors for crushing the intermediate portions of the plants as they are so conveyed, and shaker means operable in said space at intervals between the crushing movements on said plants to shake the pulp free from the fibers of the plants. 85
12. In a decorticating machine the combination of a conveyor, means for feeding plants onto the conveyor bent between their ends so that the ends of the plants hang from the conveyor in adjacent relation, breaker jaws operable to crush the ends of the plants depending from said conveyor, and shaker means operable at the intervals 90 95 of crushing action on the ends of said plants for shaking the pulp free from the fibers. 95
13. In a decorticating machine for treating fibrous plants the combination of a first decorticating mechanism for horizontally receiving said plants and embodying means to crush the central portions thereof, and a second decorticating mechanism embodying conveyor means to receive the crushed central portions of said plants so that they hang 100 105 in a vertical plane from said conveyor means, said second decorticating mechanism embodying crushing and cleaning means for freeing the woody central portion from the fibrous portions of said plants. 110
14. In a decorticating mechanism the combination of a frame, a pair of spaced horizontal conveyors for horizontally receiving the ends of fibrous plants thereon with the central portions of said plants disposed in the space between said conveyors, breaking and cleaning means operating in the space between said conveyors for crushing and cleaning the central portions of said plants 115 as they are horizontally conveyed by said conveyor, a central conveyor extending from said first mentioned conveyor to receive the plants from the last mentioned conveyor at the central portions thereof whereby said plants will fall into vertical adjacent position at the ends thereof, and breaking and cleaning means operating on the ends of said plants as they are conveyed along said central conveyor. 120
15. In a decorticating mechanism the com- 125 130

bination of a frame, a conveyor carried by the frame, means for feeding plants onto the conveyor in depending vertical relation therefrom, a pair of arcuate bladed crushing 5 jaws, and means for rocking both of said bladed crushing jaws upon each other with the depending portions of the plants therebetween for crushing said plants.

16. In a decorticating mechanism the combination of a frame, a conveyor carried by the frame, means for feeding plants onto the conveyor in depending vertical relation therefrom, bladed crushing jaws, means for rocking said bladed crushing jaws upon each 15 other with the depending portions of the plants therebetween for crushing said plants, and means operating between the crushing movement of the jaws for shaking said plants after crushing of the same for freeing the 20 pulp from the fiber thereof.

17. In a decorticating machine the combination of a frame, crusher jaws, means for operating the crusher jaws to crush fibrous plants therebetween, a shaker between said 25 crusher jaws, and means for operating the shaker cooperatively connected with said means for operating the shaker at intervals between the crushing movements of said jaws.

30 18. In a machine of the class described the combination of a conveyor mechanism

including a frame and a conveyor belt, means for scutching the fibers between their ends and feeding them in depending doubled relation upon said conveyor belt, crusher and 35 cleaner means for the depending ends of said plants, and shaker means disposed between the depending portions of the plants adapted to agitate the plants after the same are crushed for freeing the pulp from the fiber 40 thereof.

19. In a decorticating machine the combination of a conveyor, a pair of pivotally mounted segmental shaped crusher jaws having convex bladed crushing faces, and means 45 for synchronously operating said jaws for a crushing rocking action on each other thru a limited arc of movement.

20. In a decorticating machine the combination of a conveyor, means for breaking 50 plants intermediate their ends in advance of the conveyor, means for feeding the plants onto the conveyor at their intermediate broken portions so that the plants bend at said intermediate broken portions and have 55 their ends depending in vertical adjacent substantially parallel relation, and breaker jaws for receiving the depending portions of said plants therebetween as the plants are carried by said conveyor for crushing the 60 end portions of said plants.

EDWARD L. PENDLETON.
